UNITED STATES PATENT OFFICE.

JOHN J. HALLIWELL, OF TUCKAHOE, NEW YORK, ASSIGNOR, BY MESNE ASSIGNMENTS, TO R. HOE AND CO., INC., OF NEW YORK, N. Y., A CORPORATION OF NEW YORK.

MULTIUNIT PRINTING MACHINE.

Application filed September 25, 1924. Serial No. 739,758.

This invention relates to certain improvements in rotary printing machines.

It is the especial object of the invention to provide an improved press arrangement comprising a series or sets of units, each set including a plurality of units and each unit including a printing and perfecting mechanism, these sets of units being provided with driving mechanism and folders so that the product of all the units of each set may go to one folder or the end units of the sets may be coupled to form other series which may run independently of the remaining units of the series from which such end units have been disconnected, the products of such second series going to folders of their own so that the end of cylinders of any set or series may be connected to drive with the other units of such sets or may form sets independent of the original sets so that a wide range of combinations of the units may be obtained. In this arrangement each set of units will be provided with its own driving mechanism and with its own folder, and the driving mechanism and folders may be used without interference with one another and no changes in the driving mechanism, other than disconnecting a clutch or gear, is necessary to transform the sets of units into sets having different numbers of units.

With this and other objects not specifically referred to in view, the invention consists in certain novel arrangements and combinations of the printing couples, the driving mechanism and folders therefor which will be fully described in connection with the accompanying drawings and the novel features then pointed out in the claims hereunto annexed.

Referring now to these drawings,—

Figure 1 is a diagrammatic plan view of a series of sets of units arranged in parallel lines and connected to deliver products in five unit combinations, and in which the units of all the sets are arranged in tandem;

Figure 2 is a diagrammatic view of the folder and the drive of the upper row of units shown in Figure 1, the view being taken on line $x-x$ of that figure, in the direction of the arrow, showing the units as arranged to produce the combination shown in Figure 6 on line $x'-x'$;

Figure 3 is a diagrammatic view of the lower set of printing units shown in Figure 1, the view being taken on line $y-y$ of that fig-

ure looking in the direction of the arrow, 55 showing the presses as coupled to produce the combination shown in Figure 7 on line $y'-y'$ of that figure;

Figure 4 is a diagrammatic end view of the set shown at the left in Figure 1 on line 60 $z-z$ of that figure showing the presses as coupled to produce the combination shown in Figure 5, on line $z'-z'$ of that figure;

Figure 5 is a diagrammatic plan view 65 showing the arrangement of the units when coupled to produce a series of sets arranged with five units;

Figure 6 is a diagrammatic plan view 70 showing the arrangement of the units when coupled to produce a series of sets each including four units;

Figure 7 is a diagrammatic plan view illustrating the arrangement of the units when coupled to produce a series of sets each including three units; and

Figure 8 is a diagrammatic plan view of a modified arrangement.

Referring now to the drawings, the press selected to show the invention consists in an arrangement of thirty units arranged in 80 series of sets, each set including five units with a driving mechanism, a motor and a folder for each set. The units of each set are arranged in tandem and in frames spaced apart to provide access to the cylinders, the 85 general arrangement of the structure being rectangular. While such an arrangement has been shown it will be understood that a press arrangement embodying features of the invention may be employed in which a less 90 number of units are provided and in which the units are arranged in somewhat different ways.

In press arrangements, however, contemplated by the invention a plurality of sets of 95 units will be provided, each set including a series of units and these units will be arranged so that the end presses may be driven with the other presses of each set, or so that they may be coupled to form independent 100 sets in which the run of the webs is at right angles to the run of the web of the remaining units of the sets.

In these drawings the presses have been numbered 1 to 30 inclusive arranged in a 105 series of six sets each set including five units. Thus, set 200 will include units 1-5 inclusive, set 300 will include units 6-10 inclusive, set

400 will include units 11-15 inclusive, set 500 will include units 16-20 inclusive, set 600 will include units 21-25 inclusive and set 700 will include units 26-30 inclusive.

5 In the arrangement shown the units of each set are arranged in tandem with the cylinders extending widthwise of the frames, suitably spaced framework indicated at 201, 301, 401, 501, 601 and 701 being indicated for 10 supporting the mechanism. These frames, if desired, may be tied together by short frames 202 provided at the points required.

15 Each printing unit will include a printing mechanism including a form cylinder 203 and an impression cylinder 204 and a perfecting couple including a form cylinder 205 and an impression cylinder 206 and web guides 207 for directing the webs, as herein-after referred to.

20 Each series of units will be provided with a driving motor 208 for the series 200, 308 for the series 300, 408 for the series 400, 508 for the series 500, 608 for the series 600 and 708 for the series 700, and these motors will drive 25 line shafts 209, 309, 409, 509, 609, and 709, these drive shafts being arranged alongside the units of each set and each being common to the units of its set. Each of the sets of units will also be provided with a folder, as 30 folder 211 for the set 200; 311 for the set 300; 411 for the set 400; 511 for the set 500; 611 for the set 600 and 711 for the set 700, these folders, so as to avoid interference with other folders hereinafter referred to, being located 35 about centrally of each set of units. Each of the line shafts is provided at its ends with miters G, K and with a pair of clutches F, J.

40 Extending at right angles to the line shafts 209, etc., are upper line shafts 212, 212', these line shafts extending across the press arrangement and parallel with the axes of the cylinders of the printing units. These line shafts are provided with miter gears 213, 313, 413, 513, 613 and 713, these gears being 45 adapted to be brought into mesh with the miter gears G on the line shafts 209, etc. The line shafts 212 and 212' are also provided with clutches H, H'.

50 In the particular construction shown, on the other side of the press are a pair of line shafts 214, 215, these line shafts being arranged parallel with the axes of the cylinders of the printing units. The line shaft 214 is provided with miter gears 216, 316, 416 55 and the line shaft 215 is provided with miter gears 516, 616 and 716, these miter gears being in mesh with the miter gears K on the line shafts 209, etc.

60 The line shafts 212, 212' are connected to two driving motors B and C; the line shaft 214 is connected to driving motor D and the line shaft 215 is connected to driving motor E. Upper folders L, L' are provided for the units which may be driven from the line 65 shafts 212, 212' and the lower folders M and N

are provided for the units which may be driven from the line shafts 214, 215.

With this arrangement a different number of sets with varying unit combinations may be produced depending on the products desired. For instance, the press arrangement may be run to arrange the units in a series of six sets each including five units delivering to one folder, as shown in Fig. 5. This is accomplished by connecting the clutches F, J 75 and disconnecting the miters 213, 313, 413, 513, 613 and 713 from the miters G and the miters 216, etc., from the miters K and slipping clutch H. With this combination the drive for each set would be from the motors 80 208, 308, 408, 508, 608 and 708 and the products would go to the folders 211, 311, 411, 511, 611 and 711.

If now it is desired to arrange the press so as to operate with seven sets, each including 85 four units, the units would be coupled as shown in Figure 6. With this arrangement the clutches F would be disconnected and the clutches J connected and the miters G would be engaged with the miters 213, 313, 413, and 90 513. The miters K and the miters 216, 316, 416, 516, 616 and 716 would be disconnected. The clutch H would be connected and the clutch H' disconnected. With this arrangement the units 2, 3, 4 and 5 would be driven from motor 95 208 and delivered to folder 211. The units 7, 8, 9 and 10 would be driven from motor 308 and delivered to folder 311. The units 12, 13, 14 and 15 would be driven from motor 408 and delivered to folder 411. The units 100 17, 18, 19 and 20 would be driven from motor 508 and delivered to folder 511. The units 22, 23, 24 and 25 would be driven from motor 608 and delivered to folder 611. The units 27, 28, 29 and 30 would be driven from motor 105 708 and delivered to folder 711 and the units 1, 6, 11 and 16 would be driven from motor B and delivered to folder L. When this arrangement is adopted units 21 and 26 could be cut out or could be driven from motor C 110 and delivered to folder L' as a two-unit combination.

If it be desired to drive the presses in sets of three a coupling could be arranged whereby 10 sets of three units each may be driven in accordance with the diagrammatic showing of Figure 7. When this arrangement is to be used the clutches F and J are disconnected from their line shafts, the clutch H' connected and the clutch H disconnected. 115 The miters G are engaged with the miters 213, 313, 413, 513, 613 and 713 and the miters K are engaged with the miters 216, 316, 416, 516, 616 and 716. With this arrangement the units 2, 3 and 4 are driven from motor 208 120 and delivered to folder 211; the units 7, 8 and 9 are driven from motor 308 and delivered to folder 311; the units 12, 13 and 14 are driven from motor 408 and delivered to folder 411; the units 17, 18 and 19 are driven from 125 motor 508 and delivered to folder 511; the units 22, 23 and 24 are driven from motor 608 and delivered to folder 611; the units 27, 28 and 29 are driven from motor 708 and delivered to folder 711; the units 1, 6, 11 and 16 are driven from motor B and delivered to folder L. The units 130 21 and 26 are cut out.

motor 508 and delivered to folder 511; the units 22, 23 and 24 are driven from motor 608 and delivered to folder 611; the units 27, 28 and 29 are driven from motor 708 and delivered to folder 711; the units 1, 6 and 11 are driven from motor B and delivered to folder L; the units 16, 21 and 26 are driven from motor C and delivered to folder L', the units 5, 10 and 15 are driven from motor D and delivered to folder M and the units 20, 25 and 30 are driven from motor E and delivered to folder N. Thus the press arrangement may be run as a series of ten units, each set comprising three printing couples.

5 It will be observed that the press arrangement shown may be utilized for a number of sets each including two printing units.

It will be observed that the cylinders all have their axes arranged parallel with each other and the printing units are all in the same plane. Where the press is coupled so as to drive around the corner, as where the units are coupled as shown in Figures 6 and 7 for instance, suitable turning bars indicated generally by the numeral T and guide rolls indicated by the numeral S are provided for suitably turning the webs of the end units to properly direct them to their respective folders.

20 In Figure 8 is illustrated another arrangement which can be employed. In this figure are diagrammatically shown two parallel lines of presses a, b, each made up of six printing units, a¹, a², a³, a⁴, a⁵, a⁶, and b¹, b², b³, b⁴, b⁵ and b⁶, arranged with their cylinders parallel. Each line of presses has a line shaft c, c¹; driving motors d, d¹, d², d³, and a folder e, e¹. Extending at right angles to the line shafts c, c¹ is a shaft f driven from a driving motor f¹. Additional folders e², e³, are provided at the ends of the lines, and a side folder e⁴ at the side of one of the lines. The line shafts c, c¹ are provided with gears g, g¹ and the shaft f is provided with gears g². The line shafts c, c¹ have clutches h, h¹, h², h³, and the line shaft f has a clutch h⁴.

With this arrangement the two end units at one end of the lines may be disconnected from the lines and coupled to form an independent unit with the webs running at right angles to the other webs, so that the press may be coupled to run as three series of four units each, or as four series of three units each. This may be done as follows: To run as three series, the gears g¹, g², are connected, and the clutches h¹, h³, unclutched, and the clutches h, h², clutched; units a¹, a², a³ and a⁴ run as one unit, driven from motor d and deliver to folder e; units b¹, b², b³ and b⁴ run as a unit driven from motor d² and deliver to folder e¹; units a⁵, a⁶, b⁵, b⁶, run as a unit driven from motor f¹ and deliver to side folder e⁴.

To run as four series, gears g¹, g² are disconnected; clutches h¹, h³, clutched; and

clutches h, h², unclutched; units a¹, a², a³, drive from motor d and deliver to folder e; units b¹, b², b³, drive from motor d² and deliver to folder e¹; units a⁴, a⁵, a⁶, drive from motor d¹ and deliver to folder e²; units b⁴, b⁵, b⁶, drive from motor d³ and deliver to folder e⁴. It will be understood that by duplicating, etc., the arrangement of Figure 8, various other press combinations may be obtained. It will also be understood that suitable bars and guides will be provided for guiding the webs to the folders in the various press combinations.

While the invention has been shown and described in its preferred arrangement and with certain combinations which can be provided by suitably coupling the units, it will be understood that the invention is not to be restricted to the particular arrangement shown, that by the addition of further units other and larger combinations could be provided and those shown and described are merely illustrative of the invention.

What is claimed is:

1. The combination of sets of printing units arranged in parallel lines, a folder and driving mechanism for each line, said folder being located between the units, means whereby the end units of the lines at both ends may be coupled to form lines of units independent of the units therebetween, and a folder and driving mechanism for each of the latter lines.

2. The combination of a series of printing units arranged in lines, a folder for each line, a line shaft for each line extending transversely to the axes of the units, a line shaft extending parallel with the axes of the units, means for coupling the end units to either of the line shafts, and means for driving the line shafts independently.

3. The combination of a series of printing units arranged in lines, a folder for each line, a line shaft for each line extending transversely to the axes of the units, line shafts on each end of the units and parallel with the axes of the units, means for coupling the end units to the transverse or parallel shafts, means for driving the line shafts independently, and folders for the units irrespective of their coupled relation with the shafts.

4. The combination of a plurality of printing units arranged in line, a plurality of printing units arranged in line at an angle to the first line, a folder and driving mechanism for one line, said folder being located between the units, a folder and driving mechanism for the other line, and means whereby the unit forming the end unit of both lines may be coupled to run with either line.

5. The combination of a plurality of printing units arranged in line, a plurality of printing units arranged in lines at each end of the first line and at an angle thereto, a

- folder and driving mechanism for each line, and means whereby the units forming the end units of the lines may be coupled to run with either line. 60
5. 6. The combination of a series of printing units arranged in line, a series of printing units arranged in a line parallel with the first series, units between the lines, means for coupling the end units of each of the lines 65 with the units therebetween to form other series of units, folders, and web guides for guiding the webs to the folders.
7. The combination of a series of printing units arranged in line, a series of printing units arranged in line parallel with the first series, printing units between the lines, and means for coupling the end units of the lines with the units therebetween to form other series of units. 70
10. 8. The combination of a series of printing units arranged in line, a series of printing units arranged in line parallel with the first series, a folder for each of the series, printing units between the lines, means for coupling the end units of the lines with the units therebetween to form other series of units, and a folder for each series so formed. 75
9. The combination of a series of printing units arranged in line, a series of printing units arranged in line parallel therewith, a line shaft in each series extending along the units, printing units between the lines, line shafts for such units extending at right angles to the first shafts, means for coupling the end units of the series to either shaft to form other series, and a folder for each series. 80
10. The combination of a series of units arranged in line, a series of units arranged in line parallel therewith, printing units between the lines, the cylinders of all the units being parallel, means for coupling the end units of each series to the units therebetween to form other series, a folder for each series, and web guides for guiding the webs to the respective folders. 85
11. The combination of a series of thirty printing units arranged in parallel lines, a folder for each line, and means for coupling the units to run as six series of five units each without an idle folder in a series. 90
12. The combination of a series of thirty printing units arranged in parallel lines, a folder for each line, and means for coupling the units to produce seven series of four units each and one group of two units, with a folder for each series and for the group, without an idle folder in the lines. 95
13. The combination of a series of thirty printing units arranged in parallel lines, a folder for each line, and means for coupling the units to produce ten series of three units each, with a folder for each series, without an idle folder in the lines. 100
14. The combination of printing units arranged in a series of parallel lines, means for coupling two end units at one end of the lines to form a line of units at right angles to the remaining units, and folders between the units of the lines. 105
15. The combination of printing units arranged in a series of parallel lines, means for coupling the end units at each end of the lines to form lines of units at right angles to the remaining units. 110
16. The combination of printing units arranged in a series of parallel lines with the cylinders of the units parallel, a folder for each line, means for coupling two end units at one end of the lines to form a line of units at right angles to the remaining units, a folder for such line at right angles to the first folders, and means for guiding the webs to the folders. 115
17. The combination of printing units arranged in a series of parallel lines with the cylinders of the units parallel, a folder for each line, means for coupling the end units at each end of the lines to form lines of units at right angles to the remaining units, a folder for each line so formed at right angles to the first folders, and means for guiding the webs to the folders. 120
18. The combination of four lines of printing units, each line including five printing units, of means for coupling the units to form five lines of printing units, each line including four printing units, and a folder for each line. 125
19. The combination of three lines of printing units, each line including five printing units, of means for coupling the units to form five lines of printing units, each line including three printing units, and a folder for each line. 130
20. The combination of a series of printing units arranged in lines, a folder for each line, a line shaft for each line extending transversely of the axes of the units, line shafts extending parallel with the axes of the units, means for coupling the end units with either of the line shafts, means for driving the line shafts independently, folders, and web guides for guiding the webs to the folders. 135

In testimony whereof, I have hereunto set my hand. 140

JOHN J. HALLIWELL.
